COMBINED THERMOSTATIC AND TIME
HEAT CONTROL FOR STOVE OVENS

Benjamin Edward Meacham, Lorain, Ohio, assignor to American Stove Company, St. Louis, Mo., a corporation of New Jersey

Application August 26, 1932, Serial No. 630,606

13 Claims. (Cl. 236—15)

This invention relates to an improvement in a combined thermostatic and time heat control for stove ovens and is a construction particularly adapted and suited for use in connection with the ovens of domestic gas cooking stoves or ranges.

The primary object of the invention is the provision of a new and improved heat control for stove ovens.

10 A further object of the present invention is the provision of a thermostatic oven heat control in combination with a time control which is automatic in operation and is still so designed and constructed as to be safe and efficient in operation.

Another and primary object of the present invention is the provision of an improved thermostatic oven heat control so constructed as to make it possible to maintain in the oven a given heat 20 of a lower temperature than it has been possible heretofore to successfully maintain in a stove oven.

Another and further object of the invention is the provision of an oven heat control which is so constructed as to eliminate to the greatest possible degree the possibility of a flash back at the time the oven burner is ignited.

25 A still further object of the invention is the provision of a new and improved snap action temperature control valve.

A still further object of the invention is the provision of a thermostatic oven heat control wherein the heat regulator governs the gas supply to a pilot valve which in turn governs the gas 35 delivery through the heat regulator to the oven burner.

Other specific objects and novel features of construction and improved results of the invention will appear in more detail in the following 40 description when read in the light of the accompanying drawings.

In the drawings:

Figure 1 is a view in front elevation of a gas range equipped with the present heat control.

45 Fig. 2 is an end view of the range, a portion of the stove being broken away and shown in section to more clearly illustrate the construction.

Fig. 3 is a top plan view of the range.

Fig. 4 is a rear view of the range.

50 Fig. 5 is a sectional view through the snap action pilot control gas valve.

Fig. 6 is a rear view of the thermostatic heat regulator.

55 Fig. 7 is a vertical sectional view through the heat regulator.

Fig. 8 is a front view of the heat regulator.

Fig. 9 is a sectional view taken on the line 9—9 of Figure 7 looking in the direction indicated by arrow.

Fig. 10 is a detailed view in elevation of the time controlled valve and the clock for operating the same.

Fig. 11 is a rear view of the range illustrating a modified form of the invention.

In the drawings a conventional type of domestic gas cooking range is illustrated, A designating the cooking top portion of the range and B and C the ovens thereof.

With the conventional range in mind the present invention will first be described in broad 15 terms and details of the construction brought out later in the description.

D is a thermostatic heat regulator and E is a clock for controlling the valve F. Both the regulator and the clock are preferably positioned at and above the rear edge of the oven top but they need not essentially be so positioned.

A thermostatically operated valve is designated at G and is in the main gas or fuel supply line H. A gas supply line from this valve G to the 25 oven burner K is designated at L. A gas or fuel conduit M joins the thermostatic regulator D and the thermostatic valve construction G. A gas conduit N connects the thermostatic regulator with the time controlled valve F. A gas conduit O connects the time operated valve F with the pilot light P which is positioned in the cooking top burner chamber adjacent the oven burner.

A thermostatic element Q for operating the thermostatic valve G extends into the cooking top burner chamber and over the pilot light P. The thermostatic regulator D has a heat responsive element R which is positioned in the oven where it is subjected to the heat temperature thereof.

Upon describing the present heat control in detail attention is directed to the fact that the present control mechanism works on the principle that the oven heat regulator turns on and off the gas supply to the safety pilot light P and 45 the presence or absence of flame at this pilot light controls the delivery of fuel to the oven burner. This is a departure from the principle of operation of oven heat regulators now known and in use in that heretofore the regulator has directly controlled the delivery of fuel to the burner by being positioned in the fuel line to the burner.

It is due to the particular and novel manner of operation of applicant's heat control together 55

with certain other specific features which will be hereinafter described in detail, which enable applicant's heat control to maintain in the oven a given temperature which is lower than it has been heretofore possible to maintain in the oven of a domestic gas cooking range.

Heretofore it has not been possible to maintain a minimum temperature of less than 300° F. in a well insulated oven, whereas in applicant's present improved heat control tests have proven that a temperature as low as 200° F. can be maintained for as long a period as desired. Maintenance of a continued low temperature in the oven is accomplished by completely extinguishing the flame at the oven burner when the heat regulator acts whereas heretofore when the regulator went into action it did not completely extinguish the flame at the oven burner for the reason that a by-pass fuel passageway has always been provided for maintaining at the burner a small flame. The by-pass had to be large enough to provide sufficient fuel to support a flame at all the ports of the oven burners to prevent unburnt gas and other obnoxious gasses from escaping into the oven and thence into the room. In addition there was a pilot light fire which burned as long as the oven was in operation. As a consequence there was in the oven, even when the heat regulator was closed, the maintenance of a considerable amount of flame which produced a considerable amount of heat. Consequently, the pilot light and the minimum fire at the oven burner when the regulator was closed cause a building up of oven heat temperature which made it impossible to maintain in a well insulated oven a thermostatically controlled heat lower than 300° F.

To the end that the present invention will be more fully understood and the significance and importance of applicant's heat control being able to provide for a maintained heat of less than 300° F. in the oven, a detailed description of the parts and mechanism going into the make-up of applicant's improved heat control will now be given.

Having reference particularly to Figures 2, 3 and 4 of the drawings it will be seen that the fuel conduit H to the safety thermostatically controlled valve G is connected to the main fuel supply manifold S of the gas range in the burner chamber beneath the cooking top portion of the range, as clearly indicated at 10 in Figure 2 of the drawings. The admission of fuel to the conduit H is under the control of a valve which has an elongated operating handle 11 positioned at the front of the cooking top portion of the range. A small constantly burning flame is maintained at a constant burning pilot light T. This pilot light T is in the range oven and receives its gas through a conduit 12 which is connected to the main supply manifold S as at 13. It is to be noted that the safety pilot light P is of a T-shape in that it has a portion 14 in the burner chamber of the cooking top portion of the range and it is this portion of the pilot light which is immediately beneath the thermo element Q of the safety thermostatic valve G. The leg portion 15 of this pilot extends into the oven and terminates adjacent the constant burning pilot T. The oven burner will of course be ignited, when gas is supplied to it, by the flames of both the pilots P and T.

Having reference now to the thermostatically operated safety valve G which is illustrated in

detail in Figure 5 of the drawings, here it will be seen that there is a housing 16 which is divided into a chamber 17 and a chamber 18 by a valve 19. There is a second housing 20 having therein a chamber 21. The housing 16 has a hollow threaded extension 22 which is threadedly connected to the housing 20 and communication between the chamber 18 of the housing 16 and the chamber 21 of the housing 20 is had through this tubular extension 22. The gas conduit L to the oven burner is in communication with the chamber 17 and the gas supply pipe H from the main gas or fuel supply manifold S communicates with the chamber 18. Thus the valve 19 which is normally held on its seat by a coil spring 23 will normally close communication between the fuel inlet to the chamber 18 and the fuel outlet from the chamber 17 to the oven burner. Fuel however, even when the valve 19 is closed, can pass into the chamber 21 and from that chamber by the pipe M to the thermostatic regulator D.

The thermo element Q is supported by the housing 20. This thermo element is a copper tube 24 containing a rod 25 of some suitable non-expansive material which has its end 26 extending into the chamber 21 for engagement with the pivotally mounted lever 27, which lever in turn is in operative engagement with the pivotally mounted lever 28. A carrier 30 is reciprocable within the chamber 18 and is provided with an elongated stem 31 having an enlarged head 32 behind which is a coil spring 33 which tends normally to hold the head 32 in engagement with the pivotally mounted lever 28 which will in turn cause engagement between this lever and the lever 27 and engagement between the lever 27 and the end 26 of the rod 25 of the thermo member Q.

The valve 19 is provided with a rod extension into the chamber 18 and this rod extension carries a cone 34 intermediate the length of the rod while the end 35 of the rod reciprocably carries a head 36 which is held normally in engagement with the inturned ends 37 of a pair of pivotally mounted levers 38 by a coil spring 39. These levers are pivotally mounted on the carrier 30 as at 40 and their ends are provided with rollers 41 adapted to engage the cone 34 of the valve stem extension.

In operation when the copper tube 24 of the thermo element Q is heated it expands or lengthens thus permitting the spring 33 to move the carrier to the left. This movement of the carrier will cause the rollers 41 to roll up the cone 34 and then down the rear side of the cone. Immediately the rollers reach the rear side of the cone the spring tension inserted on the arms carrying the rollers by the spring 39 will cause the valve 19 to open with a snap. The degree to which this valve 19 opens is under the control or regulated by a set-screw 42.

It will be obvious that when the copper tube 24 cools the reverse action will take place and the valve 19 will snap closed under the tension built up in the coil springs 23 and 39.

It is the snap action of this valve which controls the admission of fuel to the oven burner which eliminates to the greatest possible degree the likelihood of a "flash back". Applicant has discovered that a "flash back" is most likely to occur with a very lean mixture of gas and air in the burner, which condition is most likely to occur if the gas to the burner is turned on slowly. Thus by snapping the valve open for delivery of a full supply of gas to the oven burner the likeli-

hood of a "flash back" is to a large degree eliminated.

It is to be understood however that the present heat control is not dependent upon a snap action valve as in a recent test with a quick acting throttling valve operated by bi-metal thermo element a minimum temperature varying between 185° F. and 190° F. was maintained in the oven of a cooking range. The gas to the oven burner was on fifteen seconds in every six minutes. It was found that each cycle was six minutes long although the duration of a cycle would vary in accordance with the degree of insulation of the stove oven.

15 Coming now to the heat regulator the construction of which is illustrated in detail in Figures 6 to 9 inclusive of the drawings, it will be apparent that this device is comparatively simple in construction.

20 As previously mentioned the thermostatic element is designated at R and is preferably a strip of bi-metal one end of which is secured as at 43 to the regulator housing or carrier 44 while its opposite end 45 is in engagement with a cap 46 carried by a stem 47 which is reciprocable within a guide sleeve 48 and has its opposite end 49 adapted for engagement with a valve 50. The valve 50 is positioned within a housing 51 and when in engagement with its seat 52, as it normally is by reason of a coil spring 53, divides this housing into two chambers 54 and 55. The fuel pipe line M from the safety valve G communicates with the chamber 55 and the fuel pipe line N which interconnects the regulator and the time operated valve F communicates with the chamber 54. Consequently fuel can pass to the time operated valve only when the valve 50 of the regulator is open.

It is intended of course that the regulator housing or support 44 be so positioned that the thermo element R is in the stove oven and subjected to the heat therein. The expansion and contraction of this thermo element causes the opening and closing of the valve 50. A lever 56 pivotally mounted as at 57 forms a part of the regulator mechanism. A pin 56 passes loosely through the lower end of this lever and at one end carries a saddle 59 over which passes an intermediate portion of the thermo strip R. A pin 60 extends across the saddle above the thermo strip and the pin or stem 58 beyond the lever is provided with a cotter key 61. As a consequence the pin or stem 58 can be moved by moving the lever. The lever is moved to alter the position of the thermo strip to effect the temperature adjustments at which the valve 50 will be opened by the thermo member. To move the lever 56 and to obtain this temperature adjustment the regulator is provided with an adjusting stem 62 threadedly mounted as at 63 in the upper end of the regulator housing or support 44. The upper end of the lever 56 is bifurcated as at 64 and engages the inner end of this adjusting stem behind its head 65. The outer end of the adjusting stem is provided with a dial 66 (see Figure 1) by means of which a careful calibration of the temperature setting or adjustment can be had.

The time operated valve F is of an extremely simple construction in that it comprises a valve (not shown) within a suitable housing 67 and having a stem portion 68 extending outwardly beyond the housing. A clock E is positioned to have operative engagement with this valve extension 68. The clock is provided with an ordinary time dial 69 and in addition with an "on"

dial 70 and "off" dial 71. Each of these dials is provided with a setting hand and by the manipulation of these hands in conjunction with the clock mechanism an opening of the valve can be had at any desired time and a closing of the valve can be had at any desired time.

It is not believed necessary to go into a minute and detailed description of the clock mechanism which effects the valve manipulation in that many such devices can be bought on the open market and the particular construction which effects the opening and closing of the time operated valve forms no part of the present invention. In so long as a dependable clock mechanism for effecting the opening and closing of the valve is provided the proper operation of the heat control is assured.

A modified form of the invention is illustrated in Figure 11 of the drawings. Relative to this modification it is suffice to say that it is exactly like the preferred form of the invention with the exception that the time operated valve has been eliminated. It is of course possible that someone might desire an installation of the present heat control without the time control feature. When the time control feature is eliminated the clock E and the clock operated valve F are dispensed with as are also the pipe lines N and O. In this form of the invention the fuel is brought from the heat regulator E to the safety pilot light P by the pipe line W which pipe line incidentally supplants the eliminated pipe conduits N and O.

Operation

A short description of the operation seems advisable.

The present heat control has of course been developed to make it possible for the housewife to cook in her absence from the kitchen or home. To accomplish this end the housewife decides the length of time as well as the temperature required to accomplish the cooking desired. Having determined this she sets the heat regulator at the desired temperature and sets the on and off dials of the clock at the proper times to turn the gas positively on and off to the safety pilot light P. She also opens the gas valve 11 so that gas can flow from the main fuel supply manifold S to the safety control valve G. Gas is being constantly supplied at all times to the constant burning pilot light T and this pilot light is at all times ignited. If this constant burning pilot light should for any reason become extinguished the entire heat control would fail to function but no gas would be supplied to the oven burner so there would be no danger of escaped unignited fuel.

Having prepared the range for its automatic operation it will be assumed that the time has been reached for the turning on or opening of the clock operated valve.

Gas or fuel has entered the chamber 18 of the safety valve G and from this chamber entered the chamber 21 and from that chamber been conveyed from the pipe M to the chamber 55 of the heat regulator. The oven being cold the thermo element R is forcing the valve 50 into an open position thus permitting the flow of fuel into the chamber 54 and from that chamber by the pipe N by the time controlled valve which now being open permits fuel to pass through the pipe O to the safety pilot light P.

The fuel reaching the safety pilot light P is ignited by the constant burning pilot light T, and in the course of a few seconds the flame

from the safety pilot P heats the thermo element Q of the safety valve G sufficiently to cause its expansion and thus permit the spring 33 to act to open the valve 19 with the snap action 5 heretofore described. The valve 19 having snapped open fuel immediately passes into the chamber 17 of the regulator and from that chamber by the pipe L into the burner K where it is ignited by both the constant burning pilot T and the portion 15 of the safety pilot light P.

10 The burner will remain lighted until the oven reaches the set temperature at which time the thermo member R of the regulator will act to permit the coil spring 53 of the valve 50 to close this valve and thus cut off delivery of gas to the time controlled valve and from that valve to the safety pilot light P. The thermo element Q of the safety valve G being subjected only to the heat of the safety pilot light will cool when this pilot light is extinguished and in a few seconds 15 time the valve 19 of the safety valve G will close and cut off the delivery of gas to the pipe L to the oven burner.

15 When the oven has cooled sufficiently to permit the heat regulator valve 50 to again open the operation heretofore described will be repeated and this cycle of operation will continue to repeat itself to maintain in the oven the set temperature of the regulator.

20 30 When the time is reached to cause the time operated valve to be permanently closed this action will take place and the heat control will fail to function further unless it is again set. When the housewife returns she will find the oven burner and safety pilot light extinguished and the food in the oven properly cooked as she had anticipated.

25 40 The operation of the modified form of the invention will from the foregoing be obvious in that it will be identical with the exception that the heat control will continue its cycles of operation until the gas valve 11 is manually closed.

45 50 From the foregoing it will be seen that a new method of automatic safety ignition for oven burners and of combined oven heat and time controlled regulated temperature is provided and that the present heat control permits of maintaining a lower set temperature in the oven than has been heretofore possible. That the possibility of "flash back" has been greatly eliminated and that the heat regulator can be simplified in its construction as it is not necessary to provide a by-pass gas passageway to maintain at the oven at all times a minimum flame is evident.

55 60 65 70 75 To prevent injury to the thermostatic element Q which would result in the event the safety pilot light P burned at full flame or full strength throughout the operation of the stove, means is provided for reducing the size of the flame at this pilot light during the operation of the oven burner. To provide for this control the end 100 of the housing 16 communicates with the tubular extension 22 through an opening 101 which acts as a valve seat for the tapered portion 102 of the elongated stem 31 of the carrier 30. It will be obvious that when the valve 19 is open for delivery of fuel to the oven burner through the conduit L the tapered portion 102 of the stem 31 will have approached the opening 101 and partially closed it to reduce the amount of fuel which passes through the tubular extension 22 into the housing 21 and from that housing to the safety pilot light P through the conduit M. Thus, when fuel is delivered to the oven burner the amount of fuel delivery to the safety pilot light

is reduced thus reducing the flame at the safety pilot light and preventing over-heating and injury to the thermostatic element Q.

Having thus described my invention what I claim and desire to secure by Letters Patent is:

1. An improved heat control for use with a stove having an oven with a gaseous fuel burner therein and a constant burning pilot light for said burner, comprising a safety pilot light adapted to be ignited by said constant burning pilot light, a main fuel line, a thermostatically operated valve in said main fuel line for controlling the flow of fuel to the burner, a thermo member positioned in the heat zone of said safety pilot light and remote to the heat zone of the oven for actuating said valve, a second fuel line leading to the safety pilot light, a thermostatic regulator operable by the heat in said oven positioned in said second fuel line, a time operated valve positioned in said second fuel line back of said thermostatic regulator, and time operated means for operating said time controlled valve to open and close the same at predetermined times, the parts operating as and for the purpose described. 15 20 25

2. An improved heat control for use with a stove having an oven with a gaseous fuel burner therein and a constant burning pilot light for said burner, comprising a supplemental pilot light adapted to be ignited by said constant burning pilot light, a fuel line for said safety pilot light having first therein a thermostatically operated safety valve operable by the heat from said safety pilot light, and secondly therein a thermostatically operated oven heat regulator for controlling the flow of fuel through said line, and thirdly therein a time operated valve with means for opening and closing said valve at predetermined times, a fuel connection between said safety valve and the oven burner, and said fuel connection being normally closed and being opened for the delivery of fuel to the oven burner only when said safety pilot light is burning. 30 35 40

3. In a device of the character described, a stove having an oven and a heating burner therefor and provided with a cooking top portion having an enclosed burner chamber, a fuel delivery conduit in the burner chamber of the cooking top portion of the stove, a main fuel line extending from said fuel conduit to the oven burner, a safety control valve positioned in said main fuel line, said safety control valve comprising a housing divided into two parts by a valve, said valve controlling the passage of the fuel to the oven burner, a safety pilot light positioned within the burner chamber of the cooking top portion of the stove, a thermo-element positioned within the heat zone of the safety pilot light and operatively connected to the safety control valve, a constant burning pilot light in the oven adjacent the oven burner, means to cause the ignition of the safety pilot light by the constant burning pilot light, a second fuel line for the delivery of fuel to the safety pilot light, said line getting its fuel from the housing of the safety control valve at a point in front of the safety control valve, a manually adjustable heat regulator in said second fuel line at a point between the connection of said fuel line with the housing of the safety control valve and its connection with the safety pilot light, 55 60 65 70 75 80 85 90 95 100 105 110 115 120 125 130 135 140 145 controlled by said thermostatic heat regulator, the parts operating whereby the delivery of fuel to the safety pilot light is solely under the control of the thermostatic regulator and the delivery of fuel to the oven burner is solely under the control of the safety control valve.

4. A device of the construction defined in claim 3, wherein a time-operated valve is positioned in the second fuel line to the safety pilot light, whereby the delivery of fuel to said safety pilot light is under the control of both the thermostatic heat regulator and said time operated valve.

5. In a fuel control device, the combination of an oven provided with a burner having a fuel supply line, a normally closed main valve for controlling the supply of fuel to said main burner, a constant burning pilot light for said burner, a safety pilot light and a secondary fuel supply line thereto, a thermostatically operated mechanism for opening said main valve and having a thermo element positioned in the heat zone of said safety pilot light, a valve adapted to partially close the delivery of fuel to said pilot light, an operative connection between the said last named valve and the thermostatically operated mechanism to partially close said valve as the main valve is opened, a thermostatically operated heat control mechanism in the fuel line to the safety pilot light and operable by the heat from said main burner, a time operated valve in the fuel line to the safety pilot light, the parts operating as and for the purpose described.

6. In a fuel control device, the combination of an oven provided with a burner having a fuel supply line, a housing forming a portion of said fuel line and containing a normally closed main valve for controlling the supply of fuel to said main burner, a constant burning pilot light for said burner, a safety pilot light positioned exteriorly of the oven and a secondary fuel supply line thereto receiving its fuel from said housing at a point in front of the main valve, a thermostatically operated mechanism for opening and closing said main valve and having a thermo element positioned in the heat zone of said safety pilot light, said mechanism including a reciprocable member within said housing for conveying a snap action operation to the main valve, said reciprocable member including a valve portion adapted to partially close the delivery of fuel to the safety pilot light when the main valve is opened, a thermostatically operated heat control mechanism in the fuel line to the safety pilot light and operable by the heat generated in the oven by the main burner, and a time operated valve in the fuel line to the safety pilot light, the parts operating as and for the purpose described.

7. An improved automatic control for a gas range having an oven and an adjacent cooking top portion, comprising a main fuel line to the oven burner, a normally closed main valve for controlling the supply of fuel to said burner, a constant burning pilot light in said oven for said oven burner, a safety pilot light positioned exteriorly of the oven in the cooking top portion of the range and receiving gas from a secondary fuel supply line, means to cause the ignition of said safety pilot light from the main pilot light, a thermostatically operated oven heat control mechanism in said secondary fuel line and operable by the heat generated in the oven by the oven burner, a time operated valve in said secondary fuel line, said oven heat control mechanism having a thermo element extending into the oven from the rear thereof and having a temperature

setting dial supported upon the rear edge of the oven, a thermostatically operated mechanism for opening the main valve and having a thermo element positioned in the heat zone of said safety pilot light, a valve for partially closing the delivery of fuel to the safety pilot light, and an operative connection between said last named valve and the thermostatically operated mechanism to partially close said valve as the main valve is opened, the parts operating as and for the purpose described.

8. In a fuel control device, the combination of an oven provided with a burner having a fuel supply line, a normally closed main valve for controlling the supply of fuel to said main burner, a constant burning pilot light for said burner, a safety pilot light and a secondary fuel supply line thereto, a thermostatically operated mechanism for opening said main valve and having a thermo element positioned in the heat zone of said safety pilot light, a valve adapted to partially close the delivery of fuel to said pilot light, an operative connection between the said last named valve and the thermostatically operated mechanism to partially close said valve as the main valve is opened, a thermostatically operated heat control mechanism in the fuel line to the safety pilot light and operable by the heat from said main burner, the parts operating as and for the purpose described.

9. In a fuel control device, the combination of an oven provided with a burner having a fuel supply line, a fuel line containing a normally closed main valve for controlling the supply of fuel to said main burner, a constant burning pilot light for said burner, a safety pilot light positioned exteriorly of the oven and a secondary fuel supply line thereto receiving its fuel at a point in front of the main valve, a thermostatically operated mechanism for opening and closing said main valve and having a thermo element positioned in the heat zone of said safety pilot light, said mechanism including a reciprocable member within said housing for conveying a snap action operation to the main valve, said reciprocable member including a valve portion adapted to partially close the delivery of fuel to the safety pilot light when the main valve is opened, a thermostatically operated heat control mechanism in the fuel line to the safety pilot light and operable by the heat generated in the oven by the main burner, and a time operated valve in the fuel line to the safety pilot light, the parts operating as and for the purpose described.

10. In a fuel control device, the combination of an oven provided with a burner having a fuel supply line, a fuel line containing a normally closed main valve for controlling the supply of fuel to said main burner, a constant burning pilot light for said burner, a safety pilot light positioned exteriorly of the oven and a secondary fuel supply line thereto receiving its fuel at a point in front of the main valve, a thermostatically operated mechanism for opening and closing said main valve and having a thermo element positioned in the heat zone of said safety pilot light, said mechanism including a reciprocable member within said housing for conveying a snap action operation to the main valve, said reciprocable member including a valve portion adapted to partially close the delivery of fuel to the safety pilot light when the main valve is opened, a thermostatically operated heat control mechanism in the fuel line to the safety pilot light and operable by the heat from the rear of the oven by the oven burner, the parts operating as and for the purpose described.

- heat generated in the oven by the main burner, from said fuel conduit to the oven burner, a safety control valve positioned in said main fuel line, said valve controlling the passage of the fuel to the oven burner, a safety pilot light positioned within the burner chamber of the cooking top portion of the stove, a thermo element positioned within the heat zone of the safety pilot light and operatively connected to the safety control valve, a constant burning pilot light in the oven adjacent the oven burner, means to cause the ignition of the safety pilot light by the constant burning pilot light, a second fuel line for the delivery of fuel to the safety pilot light, said line getting its fuel at a point in front of the safety control valve, a manually adjustable heat regulator in said second fuel line at a point between the connection of said fuel line with the housing of the safety control valve and its connection with the safety pilot light, said thermostatic regulator operable by the heat within the oven and having means whereby the regulator can be manually set to be maintained in said oven any predetermined heat temperature, the flow in the second fuel line being controlled by said thermostatic heat regulator, the parts operating whereby the delivery of fuel to the safety pilot light is solely under the control of the safety control valve.
11. An improved automatic control for a gas range having an oven and an adjacent cooking top portion, comprising a main fuel line to the oven burner, a normally closed main valve for controlling the supply of fuel to said burner, a constant burning pilot light in said oven for said oven burner, a safety pilot light positioned exteriorly of the oven in the cooking top portion of the range and receiving gas from a secondary fuel supply line, means to cause the ignition of said safety pilot light from the main pilot light, a thermostatically operated oven heat control mechanism in said secondary fuel line and operable by the heat generated in the oven by the oven burner, a time operated valve in said secondary fuel line, said oven heat control mechanism having a thermo element extending into the oven, a thermostatically operated mechanism for opening the main valve and having a thermo element positioned in the heat zone of said safety pilot light, a valve for partially closing the delivery of fuel to the safety pilot light, and an operative connection between said last named valve and the thermostatically operated mechanism to partially close said valve as the main valve is opened, the parts operating as and for the purpose described.
12. In a device of the character described, a stove having an oven and a heating burner therefor and provided with a cooking top portion having an enclosed burner chamber, a fuel delivery conduit in the burner chamber of the cooking top portion of the stove, a main fuel line extending
- 5 10 15 20 25 30 35
13. A device of the construction defined in claim 12, wherein a time operated valve is positioned in the second fuel line to the safety pilot light, whereby the delivery of fuel to said safety pilot light is under the control of both the thermostatic heat regulator and the time operated valve.
